TRACK CART

Elvin T. Thompson, Alliance, Ohio, assignor to Lewis
Engines, Inc., Alliance, Ohio, a corporation of Ohio

Filed Feb. 13, 1961, Ser. No. 63,912

Term of patent 7 years

(Cl. D14—3)

FIG. 1

FIG. 2

FIG. 3

FIG. 4

FIGURE 1 is a top plan view of a track cart, showing my new design;

FIGURE 2 is a side elevation thereof;

FIGURE 3 is a front elevation thereof; and FIGURE 4 is a rear elevation thereof.

I claim:

The ornamental design for a track cart, as shown.
